L. WESTIN.

AIR MOTOR.

APPLICATION FILED FEB. 26, 1921.

1,412,729.

Patented Apr. 11, 1922.

Fig. 2.

Fig. 4.

This technical drawing illustrates a double-pane window frame with various numbered components. The frame consists of an outer shell (28) and an inner shell (30). The top pane is labeled 18, and the bottom pane is labeled 30. The left pane is labeled 36, and the right pane is labeled 38. The top sash is labeled 27, and the bottom sash is labeled 43. The left side of the frame is labeled 42, and the right side is labeled 40. The top edge of the inner shell is labeled 13, and the bottom edge is labeled 35. The left edge of the inner shell is labeled 33, and the right edge is labeled 34. The top edge of the outer shell is labeled 10, and the bottom edge is labeled 40. The left edge of the outer shell is labeled 12, and the right edge is labeled 23. The bottom edge of the outer shell is labeled 35.

Louis Westin
Attorney
Frank Warren

UNITED STATES PATENT OFFICE.

LOUIS WESTIN, OF BANGOR, WASHINGTON.

AIR MOTOR.

1,412,729.

Specification of Letters Patent. Patented Apr. 11, 1922.

Application filed February 26, 1921. Serial No. 447,977.

To all whom it may concern:

Be it known that I, LOUIS WESTIN, a citizen of the United States, residing at Bangor, in the county of Kitsap and State of Washington, have invented a certain new and useful Improvement in Air Motors, of which the following is a specification.

My invention relates to improvements in air motors that are adapted to be rotated by the natural draft of warm or hot air in its passage upwardly through a flue such as a chimney, smoke-stacks or the like, and the objects of my invention are to provide an air motor of balanced construction and minimized friction that will generate power to be utilized in driving a dynamo or the like.

With the above and other objects in view which will appear as the description proceeds the invention consists of the novel construction, adaptation, arrangement and combination of parts hereinafter described and claimed.

I accomplish these objects by devices illustrated in the accompanying drawings, wherein—

Figure 1 is a view in side elevation of an air motor embodying the features of my invention installed in the lower fragmentary end portion of a flue;

Fig. 2 is a top plan view of the same;

Fig. 3 is a view in longitudinal vertical section taken on a broken line 3, 3 of Fig. 2;

Fig. 4 is a top plan view of my air motor the upper half of the casing removed; and

Fig. 5 is a view in transverse vertical section taken on broken line 5, 5 of Fig. 1.

Referring to the drawings, throughout which like reference numerals designate like parts, the numeral 10 indicates the lower fragmentary end portion of a flue having a rectangular opening 11 therein.

Mounted within the lower end portion of said flue 10 and partly projecting exteriorly thereof through said opening 11 is a housing comprising a lower base portion 12 removably superimposed upon which is an upper or cover portion 13. Said cover portion is retained in place by holes therein fitting over dowel pins 14 secured within said base portion and said cover portion is held therein by suitable fastenings such as hooks and eyes 15, as shown in Fig. 3 of the drawings. It will thus be seen that the cover portion 13 is adapted to be removed for the purpose of

cleaning the motor wheel more fully herein- 55 after described.

The top 16 of the cover portion 13 is provided with an air intake 17 and an outlet opening, 18, said openings being separated by a partition 19 as shown in Figs. 2 and 3 of 60 the drawings.

Mounted within the cover portion 13 is the upper half of a substantially cylindrical casing comprising a member 20 the upper end of which is secured to the outer wall of 65 the opening 17, and a member 21 the upper end of which is secured to the inner wall of the opening 18.

The outer ends of the members 20 and 21 are seated within grooves provided in the 70 side walls of the cover portion 13 and their lower ends project slightly below the lower end of said cover portion as at 22.

Mounted within the base portion 12 is the lower half 23 of the cylindrical casing, the 75 outer ends of which are seated within grooves provided in the side walls of the base portion 12 as at 24 and the upper ends 25 project slightly above the upper end of said base portion 12 to overlap the ends 23 80 of the upper half of the casing as shown in Fig. 3.

Concentrically mounted within said cylindrical casing is a motor wheel 26 comprising end disc members 27 and 28 which are held 85 in spaced apart relation by a drum 29 secured thereto.

Fixedly secured to the drum 29 are a plurality of spaced apart vanes 30 radially projecting therefrom to the peripheries of the 90 disc members 27 and 28 and forming a series of pockets 31 therebetween.

The end disc members 27 and 28 are keyed to a shaft 32 which is provided with reduced ends 33 and 34. The reduced ends 33 is rotatively mounted in a bearing 35 secured to a bracket 36 fixed to the base portion 12 and the reduced end 34 is mounted in a bearing 37 secured to the upper end of said base portion.

The cover member 13 is cut away as at 38 and 29, to prevent frictional contact of the shaft 32 and its reduced end 34 with said cover member and stops 40 are secured to the bracket 36 and base portion 12 to prevent thrust movement of said shaft.

The bracket 36 is provided with an opening 41 and a pulley 42 is keyed to the shaft

32, within said opening, on which is mounted a belt 43 which may be connected with a dynamo or other mechanism (not shown) for the purpose of utilizing the power derived 5 from the air motor.

Referring to the drawings, it will be seen that the periphery of the motor wheel 26 is adapted to clear the cylindrical casing and partition 19 in which it is concentrically 10 mounted. The reduced ends 33 and 34 of the shaft 32 mounted in the bearings 35 and 37 form the only frictional contact between the rotary and stationary parts of the motor which friction is reduced to a minimum by 15 virtue of reducing said ends and bearings of said shaft.

The partition 19 is adapted to register flush with the upper wall of the opening 11 in the flue 10 so that when the air motor is 20 installed the intake opening 17 will be located exteriorly and the outlet opening 18 will be located interiorly of said flue.

The motor wheel 26 being finely balanced and having very little frictional resistance 25 will rotate freely when given a slight initial impulse and the draft of air drawn in through the opening 17 will strike said motor wheel tangentially. The impact of air against the vanes 30 in its passage around 30 said wheel and upwardly through the flue 10 by way of the outlet opening 18 will cause a continuous rotary motion of said wheel which may be utilized in the manner specified.

35 From the foregoing description taken in connection with the accompanying drawings, the advantages of the construction and of the method of operation will be readily apparent to those skilled in the art to which 40 the invention relates, and while I have described the principle of operation of the invention, together with the device which I now consider to be the best embodiment thereof, I desire to have it understood that 45 the device shown is merely illustrative and such changes may be made when desired as are within the scope of my invention.

What I claim is:

1. The combination with a flue, of an air 50 motor comprising a housing having an intake opening exteriorly and an outlet opening interiorly of said flue, a motor wheel rotatively mounted within said housing, vanes on said motor wheel, and a substantially cylindrical casing extending from the outer wall of said inlet opening around the periphery of said motor wheel to the inner wall of said outlet opening adapted to form a conduit for air currents passing around 55 said motor wheel in impact with said vanes.

2. The combination with a flue, of an air 60 motor comprising a base member and a cover member removably mounted thereon, said cover member having an intake opening exteriorly and an outlet opening exteriorly

and an outlet opening interiorly of said flue, a motor wheel rotatively mounted within said housing comprising end disc members a concentric drum secured to said disc member to retain same in spaced apart relation, 70 a plurality of vanes exteriorly secured to said drum projecting radially therefrom to the peripheries of said disc member, and a substantially cylindrical casing extending from the outer wall of said inlet opening 75 around the periphery of said motor wheel to the inner wall of said outlet opening adapted to form a conduit for air currents passing around said motor wheel in impact with said vanes.

3. The combination with a flue, of an air motor comprising a housing, said housing comprising a base member and a cover member removably mounted thereon, said cover member having an intake opening exteriorly 80 and an outlet opening interiorly of said flue, a shaft mounted within said housing, one end of said shaft projecting exteriorly of said housing, said shaft provided with reduced ends, bearings secured to said base 90 member adapted to operatively support said reduced ends, a pulley keyed to said shaft exteriorly of said housing, a motor wheel mounted within said housing comprising end disc members secured to said shaft, a concentric drum secured to said disc members to retain same in spaced apart relation, 95 a plurality of vanes exteriorly secured to said drum projecting radially therefrom to the peripheries of said disc members, and a substantially cylindrical casing extending from the outer wall of said inlet opening 100 around the periphery of said motor wheel to the inner wall of said outlet opening adapted to form a conduit for the passage of air currents around said motor wheel in impact with said vanes.

4. The combination with a flue, of an air motor comprising a housing, said housing comprising a base member and a cover member removably mounted thereon, said cover member having an intake opening exteriorly 105 and an outlet opening interiorly of said flue, a bracket exteriorly secured to said housing adjacent to the upper end of said base member having an opening therein, a shaft mounted within said housing, one end of said shaft projecting exteriorly of said housing through an opening therein and free 115 to contact therewith, said shaft provided with reduced ends, bearings secured to said bracket adapted to operatively support said reduced ends, a pulley secured to said shaft exteriorly of said housing and within the opening in said bracket, a motor wheel 120 mounted within said housing comprising end disc members secured to said shaft, a concentric drum secured to said disc members to retain same in spaced apart relation, a plurality of spaced apart vanes radially 125

secured to the exterior of said drum and to the inner sides of said disc members projecting from said drum to the peripheries of said disc members and adapted to form a series of air chambers, a substantially cylindrical casing extending from the outer wall of said inlet opening around and free of contact with the periphery of said motor wheel to the inner wall of said outlet opening adapted to form a conduit for the passage of air currents around said motor wheel in impact with said vanes, said cylindrical casing being divided into upper and lower members adapted to overlap the outer ends of said upper member being imbedded in the walls of said upper member of said housing, the outer ends of said lower member being imbedded in the walls of said base member of said housing, and said intake opening adapted to conduct the air in tangential impact with said motor wheel.

In witness whereof, I hereunto subscribe my name this 21st day of February, A. D. 1921.

LOUIS WESTIN.
